(57) **ABSTRACT**

A method of and system for presenting enriched video viewing analytics is presented. A method of presenting enriched statistical and analytical information includes receiving a catalog of a plurality of content items. Each content item has associated metacontent characterizing the content item. The method also includes receiving and storing operations of a user for interacting with one or more of the content items. The method further includes determining use and/or viewing statistics for, for example, the content items, metacontent associated with the content items, the numbers and types of devices viewing the content items, subscriber information, household information, and/or viewer demographic information for past and present time periods. The method also, optionally, includes estimating the likelihood of future user interaction operations.

**METHOD OF AND SYSTEM FOR
PRESENTING ENRICHED VIDEO VIEWING
ANALYTICS**

**CROSS-REFERENCE TO RELATED
APPLICATIONS**

This application claims the benefit under 35 U.S.C. §119 (e) of U.S. Provisional Patent Application No. 61/241,444, entitled Method of and System for Presenting Enriched Video Viewing Analytics, filed Sep. 11, 2009, which is herein incorporated by reference in its entirety.

BACKGROUND OF THE DISCLOSURE

1. Field of the Invention

The invention generally relates to analytics associated with audio/video content items, and, more specifically, to providing statistical and analytical information on past, present, and predicted future viewing and user-interaction operations as well as providing a structured metacontent system for content items.

2. Description of Related Art

The information regarding the subscribers and households that, at any time, are tuned to a television station or program, interacting with a video-on-demand (VOD) asset, or watching an internet video can be economically very important to content providers, advertisers and service providers. Also important is information regarding the subscribers' ongoing operations (e.g., play, pause, rewind, and/or fast-forward operations) and the video frame(s) involved in the operations at that time.

BRIEF SUMMARY OF THE DISCLOSURE

In one aspect, a method of and system for presenting enriched video viewing analytics is presented.

In another aspect, a method of determining interaction analytics for user interactions with a catalog of audio/video content items is presented. The method includes providing a predefined collection of content identifiers for identifying content items based on characteristics of the content items and providing access to a catalog of content items. A plurality of the content items of the catalog are associated with metacontent describing a corresponding content item. The method further includes analyzing the metacontent associated with at least one of the plurality of content items of the catalog and associating at least one content identifier with said at least one content item based on the metacontent associated with said at least one content item. The method also includes monitoring user interactions with the content items of the catalog and forming historical records of said interactions. The historical records include at least one content identifier associated with the content items with which the user interacted. The method further includes determining interaction analytics for at least one of a set of content items of the catalog and/or a set of users having interacted with the content items of the catalog based on the historical records of user interactions and based on at least one specified content identifier.

In yet another aspect, the method further includes identifying a type of device the user is using to interact with the content items. The determining the interaction analytics for the set of users having interacted with the content items includes determining at least one of a number of and a set of a specified type of device the users are using to interact with content items during a specified period of time. Optionally, the specified period of time is a current period of time.

2

In a further aspect, the specified period of time is a past period of time, and the method further includes estimating at least one of a number of and a set of a specified type of device users will use during a future period of time to interact with content items based on the interaction analytics determined for the past period of time.

In yet a further aspect, determining the interaction analytics includes determining at least one of a number of and a set of users performing at least one specified interaction during a specified period of time. Optionally, the specified period of time is a current period of time.

In another aspect, the specified period of time is a past period of time, and the method further includes estimating at least one of a number of and a set of users who will perform the specified interaction with content items during a future period of time based on the interaction analytics determined for the past period of time.

In still a further aspect, the determining interaction analytics includes determining at what playback position in a content item a specified user was interacting with said content item during a specified period of time. The content item being specified by the at least one specified content identifier. Optionally, the specified period of time is a current period of time.

In another aspect, the method further includes presenting a portion of the content item corresponding to the determined playback position.

In a further aspect, the interaction analytics for the set of users having interacted with the content items includes determining a set of content item preferences for at least one of the users.

In yet another aspect, the method further includes determining a time during which the at least one of the users is interacting with the content items of the catalog and presenting an advertisement for at least one content item based on the set of content item preferences for the at least one user and based upon at least one of a content identifier associated with said advertised content item and the metacontent associated with said advertised content item.

In another aspect, a method of presenting enriched statistical and analytical information includes receiving a catalog of a plurality of content items. Each content item has associated metacontent characterizing the content item. The method also includes receiving and storing operations of a user for interacting with one or more of the content items. The method further includes determining use and/or viewing statistics for, for example, the content items, metacontent associated with the content items, the numbers and types of devices viewing the content items, subscriber information, household information, and/or viewer demographic information for past and present time periods.

In a further aspect, the method includes estimating the likelihood of future user interaction operations based on the received interaction operations and metacontent associated with the content items.

In yet another aspect, named entities are associated with at least one of the content items based on the metacontent associated with said content item. The information associated with the named entities complies with a predetermined information hierarchy.

In still a further aspect, the statistics determined include one or more of the number and set of viewing devices currently interacting with the network, the number and set of subscribers and/or households corresponding to any one or more device(s), the identity and enriched tag and/or metacontent information associated with any one or set of content items, the current interaction operation and video frame meta-

content corresponding to each device operating on a particular content item or subset of items at a designated time, the actual image and/or video stream (or link thereto) corresponding to a video frame displayed and/or downloaded to each device operating on a particular content item or set of content items at a given time, the enriched tags associated with the past interaction operations of each device, subscriber and/or household, statistical weights associated with each device, subscriber and/or household, wherein the statistical weights are correlated with a particular device, subscriber and/or household based on learning preferences from past interaction operations, such as viewing history, demographic information and/or subscription information of each household associated with one or more particular devices.

BRIEF DESCRIPTION OF THE SEVERAL VIEWS OF THE DRAWINGS

FIG. 1 shows an illustrative service provider network for receiving system interaction operations and for providing content to a user.

FIG. 2 shows an illustrative event processing system cooperating with the service provider's network for collecting and logging system interaction operations.

FIG. 3 shows illustrative components of the event processing system of FIG. 2 for retaining user interaction operations and generating analytics.

FIG. 4 shows an illustrative process for populating or updating a universal smart tagging subsystem.

FIG. 5 shows an illustrative process for creating and/or augmenting a database of named entities.

FIG. 6 shows an illustrative process for correlating meta-content of content items of a listing with named entity information.

FIG. 7 shows an illustrative process for creating a subscriber events database.

FIG. 8 shows an illustrative process for creating a subscriber video signature database.

FIG. 9 shows an illustrative process for targeted presentation of advertisements.

DETAILED DESCRIPTION OF EMBODIMENTS OF THE INVENTION

An illustrative embodiment of the present invention provides methods of and systems for determining statistical and analytical information based on user interactions with a system that provides audio/video content to a user. The statistical and analytical information can include, for example, past, present, and predicted future content consumption by a user and user/system interaction operations. In at least one implementation, a structured metacontent system for content items is provided. As used herein, the "present" state of a device and/or system can include the last known state of the device and/or system. Further, as used herein, "audio/video content" means content having at least one of audio or video content. Thus, for example, audio/video content includes televisions programs and movie, which have both audio and video content, as well as music, which has audio content only.

FIG. 1 illustrates a service provider network 100 for receiving system interaction operations and for providing content to a user. The service provider network 100 includes service provider servers 110 for providing content items (e.g., audio/video content, television programs, videos, movies, etc.) to users requesting such items and logging user interactions with various elements of the system (i.e., tracking user actions and recording the same). The users can request, inter-

act with, and view such items on a variety of devices, including, for example, mobile devices 120 (e.g., video-enabled mobile telephones and/or mobile computing devices), television sets 130 (with or without set-top-boxes (herein "STB")), and/or computer systems 140. The service provider servers and users are connected by a subscriber network 150. The subscriber network 150 can be a private or limited access network, such as a cable system network, or the subscriber network 150 can be a public network, such as the Internet. Optionally, the service provider servers 110 can be directly connected to the users' devices.

In an illustrative implementation, service provider servers 110 include one or more home media servers 160 that are used to provide content items directly to a presentation device 170 and/or other user devices for presentation. In another implementation, one or more home media servers 160 are separate from service provider servers 110 but are able to receive content items from servers 110. The home media server 160 can be located in a user's home or other location remote from other service providers' servers. The home media server 160 can provide a search and/or storage service that allows user devices to find particular content items. The content items can include music, audio/video content (e.g., movies, television shows, web clips, etc.), still-images, and other types of content. Once found, the content items can be directly served to a presentation device for listening and/or viewing, or the content items can be transferred to another device for later consumption by the user.

Content items of any of multiple known formats can be simultaneously stored in the home media server 160. For example, music can be in the form of WAV, AIFF, MP3, WMA, and/or other types of files. Still-images can be in the form of GIF, JPEG, PNG, and/or other types of files. Live television broadcasts (e.g., over-the-air or through a network connection) can be provided through the home media server 160 as can content items stored on a Personal Video Recorder device. A Digital Video Recorder function can be performed by the home media server 160. Moreover, any number of content items can be presented in a collection-style format. For example, multiple still-images can be presented in the form of a slide show, or several songs can be grouped and presented in an album format.

Upon a user interacting with the service provider network 100, the service provider servers 110 receive and log each interaction operation and/or command. In addition, the servers 110 can, optionally, respond as appropriate to each operation, e.g., if content is requested, the servers 110 transmit the requested content. However, the servers 110 are not required to serve the content items requested by the user. Further still, the servers 110 can receive a record of interaction operations and/or commands that have been temporarily stored in a different device. For example, in a television system, an STB initially receives the user's tuning command and responds by tuning the television to the appropriate channel. The STB also logs the tuning command and transmits a record of the tuning action, along with other user interactions, to the servers 110 at a later time. In an embodiment including the home media server 160, described above, the home media server logs the interaction operations and commands for later transmittal to the servers 110. In other implementations of the service provider network 100, the servers 110 log television tuning operations (including digital video recorder (DVR) operations), video-on-demand system interactions, and/or internet video click operations (from, for example, an STB and/or computer or mobile devices). The servers 110 also log these, and other, operations in real-time and store the information in

logs for near-instantaneous data. This information is transmitted to an event processing system, described in greater detail below.

FIG. 2 illustrates an event processing system 210 cooperating with the service provider servers 110 for collecting and logging system interaction operations. If included in the system, a home media server, described in more detail above, may communicate directly with the event processing system 210 or by way of servers 110. The servers 110 and event processing system 210 communicate via a network 220. Network 220 can be a private or limited access network between the servers 110 and system 210. In addition, network 220 can include the Internet. All operations, user interaction, commands, and content item use data (herein “Event Logs”) are transmitted over network 220 from the servers 110 to the event processing system 210.

FIG. 3 illustrates components of the event processing system 210 of FIG. 2 for retaining user interaction operations, system use data, and generating analytics. The event processing system 210 includes a persistent event database 305 that correlates the information from the Event Logs with, e.g., television electronic program guide (EPG) listings, VOD asset listings and Internet video listings. Thus, the persistent event database 305 provides, for example, for each device using the service provider network 100, the current state of the television, STB, computer, and/or mobile device. In this context, “state” means at least the specific channel and/or program identifier currently being presented on the device, as well as how far into the content the presentation has progressed (e.g., the playback counter value). Database 305 can also provide the specific VOD asset identifier and the current playback position in the device’s video stream, the program identifier corresponding to the DVR recording or internet video and current playback position in the DVR recording or internet video, as well as the current video frame, the current operation (e.g., play, pause, rewind, and/or fast-forward) being performed at any time, including in real-time as well as any past-time, and the entire interaction history of each television, STB, computer, and/or mobile device in terms of its states during previous time intervals.

The event processing system 210 also includes a universal smart tagging subsystem 310. The universal smart tagging subsystem 310 includes one or more databases for the storage and retrieval of information. The actual arrangement and structure of the databases described herein is not intended in a limiting sense, but is merely illustrative. The universal smart tagging subsystem 310 includes a database of named entities, each of which is associated with a globally unique identifier (GUID). The named entities include known entities, topics, and/or content items or collections with which metacontent is associated. For example, the named entities can include famous or popular personalities (e.g., actors, sports heroes, politicians, and/or musicians), musical groups, sports teams, sports tournaments or leagues, movies, television shows, scientific topics, and/or political topics. The foregoing list is illustrative only, as other types of entities are within the scope of the invention. As described in more detail below, one advantage of the use of the name entities is to permit an “accepted identifier” to be established for the entity.

The database of named entities is formed from sources of information that are known to be (or have been designated) reliable sources of information for a particular topic. For example, ESPN websites and databases can provide named entities, and associated information, for sports-related topics; the IMDb website and databases can provide named entities, and associated information, for movie-related topics; and the Gracenote® databases can provide named entities, and asso-

ciated information, for digital entertainment (e.g., music). The sources are merely illustrative, as other information sources, both public and private (e.g., amazon.com, Wikipedia, and Last.FM), can provide sources of information to use for named entities and associated information. Moreover, the database of named entities is constantly updated and improved in the sense that metacontent and popularity estimates for existing named entities may be modified to reflect the present status of the entities. Moreover, new named entities are added to the database as they are discovered. For example, as a new movie is advertised, it can be added as a named entity to the database in the universal smart tagging subsystem 310.

Metacontent that describes or is otherwise associated with the named entities is then associated with the named entities in the universal smart tagging system 310. The metacontent that becomes associated with the named entities depends on the named entity itself. For example, if a particular named entity is a movie, then the genre of the movie, character names, actor names, cities in which the movie takes place, famous quotes, other keywords, etc. are associated with the named entity. In contrast, if the named entity is an athlete, then the sport played, the athlete’s team, awards received, etc. are associated with the named entity.

FIG. 4 shows an illustrative process 400 for populating or updating the universal smart tagging subsystem 310. A data source 405 is identified that contains named entities and/or information associated with named entities, for example, a website and/or a licensed database. A data gathering tool 410, for example, an Internet website “crawler”, processes the website to capture candidates for named entities and associated information. The information that is gathered is then stored in the event processing system 210 (at 415).

Meanwhile, FIG. 5 shows an illustrative process for creating and/or augmenting the database of named entities. A new source of potential named entity candidates 505 is processed and/or a previously processed source of named entities 510 is reprocessed to identify named entity candidates from the source(s) (step 515). Each candidate is checked to determine if it is a duplicate of a named entity already present in the named entity database (step 520). If the new candidate is not a duplicate of an existing named entity, it is assigned a GUID, and it and its associated metacontent are added to the event processing system 210 databases (step 525). If the candidate is already present in the named entity database, then the metacontent associated with the candidate is added to the event processing system 210 databases and associated with the existing named entity (step 530).

The universal smart tagging subsystem 310 receives current, past, and future listings of content items from television EPG, VOD, and/or internet video sources, and determines for the metacontent descriptions for each program asset, video, and/or listing in those sources certain additional “rich tags”. In the described implementation, the rich tags are the named entities that have an association in the event processing system 210 with metacontent that matches the metacontent found the aforementioned listings. Thus, in an illustrative implementation 600, shown in FIG. 6, the metacontent for each item in a television EPG listing, VOD listing, Internet video listing, and/or walled garden (i.e., access-controlled content) 605 is correlated with the named entity information 610 in the universal smart tagging subsystem 310 (process 615) so that relationships between items of the listing and named entities are created so as to populate an enhanced listings database 345. In other words, the rich tags to be associated with the television program are determined by using intelligent heuristics to match each metacontent, or set

of metacontent, in the listing with the universal repository of metacontent descriptions for movies, television shows, and/or episodes, which are, in turn, associated with named entities. Thus, the universal smart tagging subsystem 310 and associated rich tags enable consistent and structured categorization, description, and characterization of each content item. The same is true outside the television space.

In an illustrative implementation, the intelligent heuristics used to associate content items and their metacontent with named entities includes a set of rules developed from an analysis of large collections of content items, their associated metacontent, and capturing the patterns exhibited in the collections. These rules can then be applied on multiple sets of listings information. In addition, the rules can be formed on the basis of the types of information included in professionally edited video metacontent as well as, and in contrast to, user-generated collections of metacontent. For example, one pattern discovered in such an analysis is that professionally edited video metacontent typically contains the entire title of the content item. In contrast, user-generated collections of metacontent may only include a partial title. Thus, finding a partial match between a full title (in metacontent associated with a named entity) and a partial title (in metacontent associated with the content item of a listing) would still permit an association between the named entity and the content item to be formed.

Other rules can be formed based on monitoring the behavior of users of content provider systems over time. Such a collection of rules enables the associations created by embodiments of the present invention to adapt as user content search behavior changes. For example, by monitoring the search strings submitted by users of a VOD system when searching for movies, it has been discovered that users commonly employ Roman numerals in their search string when searching for a movie that is a sequel. Thus, content items that have metacontent describing the content item as a movie and a sequel can be associated with an appropriate Roman numeral named entity.

A further example of creating a rule based on user content search and selection behavior is based on the observation that users may often forget the title of a particular movie, television show, and/or video series. However, the user more often recalls the names of the actors, actresses, and/or characters featured in the movie, show, and/or series. Thus, a rule is employed that forms an association between a named entity that is a full proper title of an item or series and the content items themselves based on the names of actors, actresses, and/or characters being present in the metacontent associated with the content item.

For example, if a particular internet video content item is listed on-line as "Bart and Homer", the universal smart tagging subsystem 310 will associate a named entity "The Simpsons" as the correct title of the video item. The system makes this association because the characters "Bart" and "Homer" are the names of two main characters in the metacontent associated with the named entity "The Simpsons" (a television show) present in the named entity database. In addition to title information, the universal smart tagging subsystem 310 can associate tags with content items for all actors associated with the content item, any topics related to the listing or subject matter of the listing, and/or any genre information characterizing the content item. Such a consistent and complete tagging system increases the accuracy of the determination of system statistics and analytics, as set forth in more detail below.

The foregoing rules are by no means exhaustive of the rules that can be employed. Rather, the rules described above are

merely illustrative of the types of rules that can be developed by analyzing large collections of content items, their associated metacontent, and capturing the patterns exhibited in the collections as well as monitoring user content search and content selection behavior. Moreover, rules can be applied individually and/or in the aggregate with other rules. In other words, an association can be made between a named entity and a content item simply by satisfying one rule alone. In addition or in the alternative, each rule can contribute a weight as to whether or not a particular named entity/content item association is to be formed. The weights contributed by all the applied rules are then combined, and the association is created if the combined value exceeds a predetermined threshold.

The event processing system 210 further includes a persistent video metacontent database 315. The persistent video metacontent database 315 stores an association between content item identifiers, the metacontent of content items listed in the television EPG, VOD, and/or internet video listings, and the corresponding computed rich tags from the universal smart tagging subsystem 310. The persistent video metacontent database 315 is populated from the output of the metacontent processing and generation of the rich tags in the universal smart tagging subsystem 310. The persistent video metacontent database 315 stores this information for both past and present content items, thereby enabling complete system analytics to be determined at any later time.

The event processing system 210 also includes a persistent video availability database 320 that stores an association between content item identifiers and their corresponding television schedule/channel information, VOD availability schedules, rates, subscription information, Internet availabilities, and other such scheduling and availability data. This availability database 320 is populated by receiving and processing the television EPG listings, VOD listings, and/or Internet video listings. The persistent video availability database 320 retains past scheduling, availability, rate, and other such data for content items that may no longer be presently available to enable later analytics generation, as described below.

The event processing system 210 also, optionally, includes a persistent household database 325 for maintaining a map of each device identifier to a particular household identifier. For example, the persistent household database 325 can include records that represent an association between a particular STB device and a particular physical address. This association can be included in the persistent household database 325 upon a user registering for a content provider service or upon receiving the STB. Such information enables the event processing system 210 to provide statistics and analytics regarding viewership on a household level. Thus, one can discover a high correlation between (1) certain television channels, television programs, and/or genres of content items and (2) particular neighborhoods and/or other geographic designations. The persistent household database 325 retains the device identifier to a household identifier association for past associations as well as present associations.

The event processing system 210 may, optionally, include a persistent demographics database 330 for maintaining a map of each household identifier to a demographic record or profile of those residents in the household. For example, the persistent demographics database 330 can include an association between (1) a physical address of a household (2) and the number of, ages of, and/or genders of the members of the household. In addition, other types of demographic information can be provided, e.g., household income, number of cars owned, etc. This information can be obtained from third party

sources that obtain and/or track such information. Alternatively, a content or service provider deploying implementations of the systems and method described herein can be the source of such information. Thus, the persistent demographics database 330 enables the event processing system 210 to generate statistics and analytics concerning what content items are being viewed by households of a certain income, for example. The persistent demographics database 330 retains past as well as present demographic information and household associations. In addition, a unique identifier, i.e., a household identifier, can be associated with, or used in place of, the physical address discussed above.

The event processing system 210 may, optionally, further include a persistent video and image database 335 for maintaining, for one or more content items, an image related to the content item, a portion of the content item, a frame identifier within the content item, and/or a link to an image or a video stream of the corresponding portion of the video. The persistent video and image database 335 retains such links, images, and/or video stream for past as well as present content items. Such an image can be used, for example, when presenting analytics and/or other statistical information about the content items. Also, the single frames and/or the portions of video content having the highest number of views can be provided and/or presented.

FIG. 7 shows a process 700 for creating a subscriber events database 350, which captures, on a per user and/or per device basis, events related to content items. As described above, the event processing system 210 captures user interaction operations and system use data in, among other databases, the persistent event database 305. In certain implementations, this information can be correlated with information in the universal smart tagging subsystem 310 and the enhanced listing database 345 to create a subscriber events database 350. As shown in FIG. 7, user/system interaction information from, e.g., the persistent event database 305 and/or user viewing logs (collectively 705), named entity information and metadata 710, and enhanced listings information 715 are correlated (step 720) to populate a subscriber events database 350.

The correlations enable the creation of a complete viewing behavior history on a user-by-user or device-by-device basis. For example, television tune events, VOD trick mode events (e.g., fast-forward, pause, rewind type events), and/or internet video selections become associated with the named entities underlying the selected content or content being operated-on at the time (in step 720). Also, metacontent associated with the named entities 710 and/or items from the enhanced listings database 715 can be associated with the user events. Thus, the actual content experienced (watched and/or heard), when the content was experienced, actions taken during the content presentation, at what point during the presentation the actions were taken, etc. all become associated with a particular user or device (e.g., mobile device, STB, etc.) and stored in the subscriber events database 350.

FIG. 8 shows a process 800 for creating a subscriber video signature database 355, which characterizes a user's viewing and/or listening behavior and can be used to capture the user's overall content preferences (called a "signature" herein). The information in the subscriber events database 350, named entity and associated metacontent databases 805, and the enhanced listings database 345 can be analyzed (step 810) to populate the subscriber video signature database 355. U.S. Pat. No. 7,774,294, filed Mar. 6, 2007, entitled Methods And Systems For Selecting And Presenting Content Based On Learned Periodicity Of User Content Selections, incorporated by reference herein, describes techniques for learning

user content viewing preferences and forming signatures there from. These techniques can be used in combination with embodiments of the present invention to create the users' signatures that are stored in the subscriber video signature database 355. Process 800 can be performed periodically, or in real-time upon request, to keep signatures current

The event processing system 210 further includes a real-time query processing system 340. The real-time query processing system 340 cooperates with the other components of the event processing system 210 to enable the generation and reporting of past and present statistics and analytics. The real-time query processing system 340 can provide information on the current state of the service provider network 100, as a whole. For example, the system 340 can provide a report on the numbers of particular types of devices (e.g., television sets versus handheld devices versus desktop computers) currently viewing content items or a genre-based breakdown of all content currently being served by the entire network 100.

Also, the real-time query processing system 340 can provide a report on the current state of a portion of the network 100, e.g., all devices currently viewing or otherwise interacting with a particular content item or tuned to a particular channel. Further still, the real-time query processing system 340 can provide a report on the current state of a particular household or device. In this context, "state" can have the same meaning given above as well as any trick mode actions currently being performed. In the context of a particular content item, state can be an indication of the number of viewers of the content item. For example, the real-time query processing system 340 can further determine "enriched" metacontent information (metacontent information associated with content items via a named entity association) and rich tags associated with one or more designated content items. The real-time query processing system 340 can also determine the identity of devices and/or households that have interacted with or are currently interacting with a specified one or more content items and/or particular portions of the one or more content items. The content items can, optionally, be specified according to metacontent and/or rich tags; an optional past timeframe can also be provided.

The real-time query processing system 340 can also determine the number and set of device identifiers, for each type of device, currently interacting with the network 100, the number and set of subscriber identifiers and/or household identifiers corresponding to any one or more device identifiers, and/or the identity and enriched tag and/or metacontent information associated with any one or set of content items (e.g., television program, VOD asset, and/or internet video). The real-time query processing system 340 can further determine the current interaction operation (e.g., play, pause, rewind, and fast-forward) and video frame metacontent corresponding to each device operating on a particular content item or subset of items at a designated time, the actual image and/or video stream (or link thereto) corresponding to a video frame displayed and/or downloaded to each device operating on a particular content item or set of content items at a given time, and/or the enriched tags associated with the past interaction operations (e.g., tuning, clickstream history, and/or other operation) of each device, subscriber and/or household.

The real-time query processing system 340 can also determine statistics associated with each device, subscriber and/or household. Because the system receives continuous state information for all devices and/or users, the system enables the determination of various weighting factors relative to particular content consumed, as well as metacontent associated with the content. For example, by using the named entities and/or rich tag associations, the system can determine

how many minutes of James Bond movies a particular STB has consumed in a given interval because each particular James Bond movie will have associated metacontent that identifies it as a James Bond move. The same is true for any of the other named entities, e.g., Red Sox games, quantum physics programs, audio/video content featuring Val Kilmer, music by Elvis Presley, etc. Further still, the system can determine weighted statics for the type of content consumed based on the associated metacontent of the content items presented, e.g., 50% television, 30% movies, and 20% music.

In an illustrative implementation, the statistical weights are correlated with a particular device, subscriber and/or household based on learning preferences from past interaction operations (such as viewing history). The real-time query processing system 340 can determine demographic information and/or subscription information of each household associated with one or more particular devices, a breakdown of past viewing habits for a given set of devices, types of devices, and/or households in terms of content items and/or metacontent and/or rich tags associated with content items. One or more devices may be specified according to demographic and/or household information in any of the illustrative examples provided herein. In other words, when conducting any of the illustrative determinations described above, the results can be limited according to demographic and/or household information.

It is understood that the types of reports, information, statistics, and analytics listed above are illustrative only, and other information can be derived by the real-time query processing system 340 based on the information contained within the event processing system 210. Likewise, any number of statistical summaries of the illustrative determinations can be provided by the real-time query processing system 340.

In addition to providing the information, statistics, analytics, and query results listed above for the past and present, the real-time query processing system 340, in combination with the other elements of the event processing system 210, enable predictive analytics to provide estimates of the same information for future points in time. In one illustrative implementation, real-time query processing system 340 determines which subscribers, devices, and/or households are presently viewing a particular channel of a television system based on near-immediate term data on interaction operations present in the persistent event database 305. The query system 340 then correlates past interaction operations for the subset presently viewing the particular channel (again, from data cataloged in the persistent event database 305) with enriched smart tag data present in the persistent video metacontent database 315. The past interaction operations are then projected to be future operations and, optionally, can have an adjustment factor applied based on the relationship between past action and future actions recorded by the system. This correlation can present viewing preferences of the subset of viewers of the particular channel as a whole as well as preferences of subgroups within the subset of viewers of the particular channel. Knowing the viewing preferences of a particular subgroup of the present viewers enables the operator of the service provider network 100 to place advertisements targeted to the particular subgroup.

FIG. 9 shows an illustrative process 900 for targeted presentation of advertisements. For example, the query system 340 determines from information in the persistent event database 305 that approximately two million viewers of a cable network are watching a particular channel at the present time (step 905). Based on information in the subscriber video signature database 355, the query system 340 estimates that

40% of the identified viewers have exhibited a particular set of preferences, e.g., for James Bond movies (step 910). In response, the operator of the cable network places an advertisement for content items consistent with the determined preferences (step 915), e.g., for a James Bond movie that is available through the cable network video-on-demand service (step 915). Although a cable television system was used as an example above, it is understood that the scope of the invention extends beyond cable television systems as a source of content items.

In addition to targeted advertisement placement, the systems and methods described herein enable comparison of specific content items as well as categories (e.g., genres) of content items, both in the past and present. For example, the system enables the determination of the number of users that watch content items associated with baseball versus the number of users that watch content items associated with basketball (where both baseball and basketball can be named entities or metacontent associated therewith). Further, the system also enables the determination of the relative numbers of views of James Bond movies versus Indian Jones movies. Further still, the system enables other comparative determinations, such as, the subjects of educational programs (math versus chemistry), the genres of movies (action versus drama), and which sports leagues (European versus Spanish) are being consumed. Moreover, the various comparisons can be qualified by time of day the content is consumed, duration of presentation of content, date on which the content was presented, as well as demographic information associated with the users consuming the content.

Likewise, statistics associated with certain portions of a content item can be compared against statistics associated with other portions of the same content item. For example, the query system 340 can determine which portions of a particular type of sporting event commands the highest viewership. For example, the system enables the determination of the number of viewers of a particular goal in the live broadcast of the 2010 World Cup, and, in particular, can determine the number of viewers who rewind to that portion of the content item to replay the goal. Further, the system can determine the number of viewers of the 2009 Super Bowl opening ceremony versus the halftime show. Further still, by correlating information in the persistent event database 305 and subscriber video signature database 355, the system can determine the number of people who are presently watching the Super Bowl halftime show who also exhibit a preference for James Bond movies. Using this information, embodiments of the invention enable a content provider or service operator to modify its content to suit a particular target audience or customer base. In addition, aspects of the invention enable a service operator to prove or validate the makeup of its viewership to advertisers or content creators.

The techniques and systems disclosed herein may be implemented as a computer program product for use with a computer system. Such implementations may include a series of computer instructions, or logic, fixed either on a tangible medium, such as a computer readable medium (e.g., a diskette, CD-ROM, ROM, flash memory or fixed disk) or transmittable to a computer system, via a modem or other interface device, such as a communications adapter connected to a network over a medium.

The medium may be either a tangible medium (e.g., optical or analog communications lines) or a medium implemented with wireless techniques (e.g., microwave, infrared or other transmission techniques). The series of computer instructions embodies all or part of the functionality described herein with respect to the system. Those skilled in the art should appre-

13

ciate that such computer instructions can be written in a number of programming languages for use with many computer architectures or operating systems. Furthermore, such instructions may be stored in any memory device, such as semiconductor, magnetic, optical or other memory devices, and may be transmitted using any communications technology, such as optical, infrared, microwave, or other transmission technologies.

It is expected that such a computer program product may be distributed as a removable medium with accompanying printed or electronic documentation (e.g., shrink wrapped software), preloaded with a computer system (e.g., on system ROM or fixed disk), or distributed from a server or electronic bulletin board over the network (e.g., the Internet or World Wide Web). Of course, some embodiments of the invention may be implemented as a combination of both software (e.g., a computer program product) and hardware. Still other embodiments of the invention are implemented as entirely hardware, or entirely software (e.g., a computer program product).

As described throughout the disclosure, the methods, systems, and techniques presented herein overcome the limitations and drawbacks of known techniques. It will be appreciated that the scope of the present invention is not limited to the above-described embodiments, but encompasses modifications of and improvements to what has been described. For example, embodiments have been described in terms of providing enhanced analytics for television viewership. However, embodiments of the invention can be implemented for audio/video content items viewed on fixed or portable computing device, such as video-enabled mobile telephones and PDAs. In addition, some of the automated steps described herein as executed on server systems can be executed on portable devices (e.g., mobile telephones, PDAs, hand-held computing devices, etc.) All such variations and modifications are intended to be within the scope of the present invention.

What is claimed is:

1. A method of determining interaction analytics for user interactions with audio and video content items, the method comprising:

retrieving, from a first database, a collection of content identifiers for identifying a plurality of content items based on characteristics of the plurality of content items; retrieving, from a second database, a catalog of the plurality of content items, each content item of the plurality of the content items of the catalog being associated with metacontent describing the respective content item; cross-referencing metacontent associated with a first content item of the plurality of content items of the catalog retrieved from the second database with the collection of the content identifiers retrieved from the first database; associating, based on the cross-referencing, a content identifier with the first content item based on the metacontent associated with the first content item;

providing, to a third database, monitored user interactions with the plurality of content items of the catalog and historical records of the user interactions, the historical records including the content identifier associated with the first content item and the user interactions including media navigation associated with the plurality of content items of the catalog at a specified period of time; determining, using the third database, interaction analytics for a second content item of the plurality of content items of the catalog and a set of users having interacted with the second content item based on the monitored user interactions and the historical records;

14

determining whether the set of users will perform a specified interaction with the second content item during a future period of time based on the interaction analytics, wherein the specified interaction is one of a pause operation, a rewind operation, and a fast-forward operation; and

identifying an advertisement associated with the second content item of the plurality of content items of the catalog based on the determination whether the set of users will perform the specified interaction.

2. The method of claim 1, further comprising identifying a type of device a user of the set of users is using to interact with the plurality of content items of the catalog, and wherein determining the interaction analytics for the set of users having interacted with the second content item includes determining at least one of a first number of and a first set of a specified type of device the set of users used to interact with the plurality of content items of the catalog during the specified period of time.

3. The method of claim 2, wherein the specified period of time is a current period of time.

4. The method of claim 2, wherein the specified period of time is a past period of time and further comprising estimating at least one of a second number of and a second set of a specified type of device the set of users will use during the future period of time to interact with the second content item based on the interaction analytics determined for the past period of time.

5. The method of claim 1, wherein the set of users is a first set of users, and wherein determining the interaction analytics includes determining at least one of a first number of and a second set of users performing the specified interaction during the specified period of time.

6. The method of claim 5, wherein the specified period of time is a current period of time.

7. The method of claim 1, wherein determining the interaction analytics includes determining a playback position in a third content item of the plurality of content items of the catalog at which a user of the set of users was interacting with the third content item during the specified period of time, and wherein the third content item was specified by at least one specified content identifier.

8. The method of claim 7, wherein the specified period of time is a current period of time.

9. The method of claim 7, further comprising presenting a portion of the third content item corresponding to the determined playback position.

10. The method of claim 1, wherein determining the interaction analytics for the set of users having interacted with the plurality of content items includes determining a set of content item preferences for at least one user of the set of users.

11. The method of claim 10, further comprising determining a time during which at least one user of the set of users is interacting with the plurality of content items of the catalog and presenting an advertisement for a third content item based on the set of content item preferences for the at least one of the set of users and based upon at least one of a content identifier associated with the third content item and metacontent associated with the third content item.

12. The method of claim 1, wherein monitoring user interactions further includes determining at least one of a video frame metacontent corresponding to each device operating on at least one content item of the plurality of content items at the specified time, an image corresponding to a first video frame displayed or downloaded, a video stream corresponding to a second video frame displayed or downloaded to each device

15

operating on the at least one content item of the plurality of content items at the specified time, and enriched tags associated with a set of operations.

13. The method of claim 1, further comprising monitoring user interactions on a particular device.

14. The method of claim 1, further comprising monitoring user interactions for a particular subscriber.

15. The method of claim 1, further comprising monitoring user interactions for a particular household.

16. The method of claim 1, further comprising monitoring user interactions for a particular population.

17. A system for determining interaction analytics for user interactions with audio and video content items, the system comprising an event processing system configured to:

retrieve, from a first database, a collection of content identifiers for identifying a plurality of content items based on characteristics of the plurality of content items;

retrieve, from a second database, a catalog of the plurality of content items, each content item of the plurality of the content items of the catalog being associated with metacontent describing the respective content item;

cross-reference metacontent associated with a first content item of the plurality of content items of the catalog retrieved from the second database with the collection of the content identifiers retrieved from the first database; associate, based on the cross-referencing, a content identifier with the first content item based on the metacontent associated with the first content item;

provide, to a third database, monitored user interactions with the plurality of content items of the catalog and historical records of the user interactions, the historical records including the content identifier associated with the first content item and the user interactions including media navigation associated with the plurality of content items of the catalog at a specified period of time;

determine, using the third database, interaction analytics for a second content item of the plurality of content items of the catalog and a set of users having interacted with the second content item based on the monitored user interactions and the historical records;

determine whether the set of users will perform a specified interaction with the second content item during a future period of time based on the interaction analytics, wherein the specified interaction is one of a pause operation, a rewind operation, and a fast-forward operation; and

identify an advertisement associated with the second content item of the plurality of content items of the catalog based on the determination whether the set of users will perform the specified interaction.

18. The system of claim 17, wherein the event processing system is further configured to identify a type of device a user of the set of users is using to interact with the plurality of content items of the catalog, and wherein the event processing system configured to determine the interaction analytics for the set of users having interacted with the second content item

16

is further configured to determine at least one of a first number of and a first set of a specified type of device the set of users used to interact with the plurality of content items of the catalog during the specified period of time.

19. The system of claim 18, wherein the specified period of time is a past period of time and wherein the event processing system is further configured to estimate at least one of a second number of and a second set of a specified type of device the set of users will use during the future period of time to interact with the second content item based on the interaction analytics determined for the past period of time.

20. The system of claim 17, wherein the set of users is a first set of users, and wherein the event processing system configured to determine the interaction analytics is further configured to determine at least one of a first number of and a second set of users performing the specified interaction during the specified period of time.

21. The system of claim 17, wherein the event processing system configured to determine the interaction analytics is further configured to determine a playback position in a third content item of the plurality of content items of the catalog at which a user of the set of users was interacting with the third content item during the specified period of time, and wherein the third content item was specified by at least one specified content identifier.

22. The system of claim 21, wherein the event processing system is further configured to present a portion of the third content item corresponding to the determined playback position.

23. The system of claim 17, wherein the event processing system configured to determine the interaction analytics for the set of users having interacted with the plurality of content items is further configured to determine a set of content item preferences for at least one user of the set of users.

24. The system of claim 23, wherein the event processing system is further configured to determine a time during which the at least one user of the set of users is interacting with the plurality of content items of the catalog and present an advertisement for a third content item based on the set of content item preferences for the at least one of the set of users and based upon at least one of a content identifier associated with the third content item and metacontent associated with the third content item.

25. The system of claim 17, wherein the event processing system configured to monitor user interactions is further configured to determine at least one of a video frame metacontent corresponding to each device operating on at least one content item of the plurality of content items at the specified time, an image corresponding to a first video frame displayed or downloaded, a video stream corresponding to a second video frame displayed or downloaded to each device operating on the at least one content item of the plurality of content items at the specified time, and enriched tags associated with a set of operations.
